(57) **CLAIM**

The ornamental design for a moveable barrier operator, as shown and described.

DESCRIPTION

FIG. 1 is a perspective view of a moveable barrier operator according to our new design, the broken lines of the container are for illustrative purposes only and form no part of the claimed design;

FIG. 2 is a side elevational view of the moveable barrier operator of FIG. 1;

FIG. 3 is a bottom plan view of the moveable barrier operator of FIG. 1;

FIG. 4 is a rear elevational view of the moveable barrier operator of FIG. 1;

FIG. 5 is a front elevational view of the moveable barrier operator of FIG. 1;

FIG. 6 is a top plan view of the moveable barrier operator of FIG. 1;

FIG. 7 is a perspective view of a moveable barrier operator according to our new design, the broken lines of the container are for illustrative purposes only and form no part of the claimed design;

FIG. 8 is a bottom view of the moveable barrier operator of FIG. 7;

FIG. 9 is a rear elevational view of the moveable barrier operator of FIG. 7;

FIG. 10 is a top plan view of the moveable barrier operator of FIG. 7; and,

FIG. 11 is a front elevational view of the moveable barrier operator of FIG. 7.
